Attorneys.

UNITED STATES PATENT OFFICE.

ALFRED COPONY, OF MOUNT CLEMENS, MICHIGAN, ASSIGNOR OF ONE-HALF TO
CHARLES P. SPICER, OF DETROIT, MICHIGAN.

COMBINATION BILL AND STUB FOR METER READINGS.

Application filed January 17, 1919, Serial No. 271,561. Renewed January 18, 1923.

To all whom it may concern:

Be it known that I, ALFRED COPONY, formerly a subject of the Emperor of Austria, having taken out first United States citizenship papers, residing at Mount Clemens, in the county of Macomb and State of Michigan, have invented certain new and useful Improvements in Combination Bills and Stubs for Meter Readings, of which the following is a specification, reference being had therein to the accompanying drawings.

The invention relates to form sheets designed for use in simultaneously recording meter readings and computing the charge for the commodity meter. In particular the invention is designed for use in connection with meter readings of gas, electricity, etc., but it is equally applicable to any use in which varying quantities of the commodity are charged for at a fixed rate per unit. A further feature of the invention is the construction by which the recording of the date of reading automatically indicates the limit date for payment at the minimum rate. Other specific features will be more fully hereinafter described.

In the drawings:

Figure 1 is a plan view of the blank showing one of the sections unfolded and another section partly turned back.

Figure 2 is a similar view showing the section which is unfolded in Figure 1 folded upon the intermediate section so as to expose its blank reverse face.

Figure 3 is a cross longitudinal section through the folded blank.

In the present state of the art it is usual to have the meters read by an inspector who makes record of the same and hands this to the central office where entry is made, the charge computed and the bill made out. It is then necessary to deliver the bill to the consumer through the mail or by messenger. It is the primary object of my invention to render the bill at the time the meter reading is taken, thus dispensing with the services of a second messenger and also the work of transcription at the central office. It is a further object to simultaneously record upon separable portions of the sheet the quantity consumed and the charge for the same, the former being returned to the office and the latter left with the customer. Still a further feature is the forming of a duplicate record on separable portions of

the second sheet so that one may be retained by the customer and the other returned with the payment.

In detail, as shown in the drawings, A is a printed blank having three portions B, C and D which may be folded to be superimposed. The section B has at one end thereof, preferably adjacent to the fold, a space B' reserved and suitably lined and marked for recording of successive meter readings, 65 together with the difference between the same, or the quantity consumed, as indicated at F. There is also a space G for the name of the company, a space H for the name and address of the customer and a space I for directions as to use. The remaining portion of the section B contains, adjacent to one edge, numbers corresponding to the days of the month, and preferably for several months with the names of the same. 70 The balance of the section B is divided by transverse lining into a series of small sections in which are printed quantities differing from each other by some fixed unit, such as one hundred. 75

The section C, which underlies and is co-extensive with the section B, is substantially a duplicate of the latter section so far as the printed matter and the arrangement of the lines and small areas are concerned. The 80 numbers corresponding to the names of the month are not, however, in the same order, but the arrangement is such that a number on the section B will register with a number on the section C advanced by predetermined intervals, such as ten days. This result is attained by placing the last ten days in advance of the remaining days of the month on one of the sections, preferably the section A. The portion J of the section B, which 85 is divided by the transverse lines into the small areas, registers with a correspondingly lined portion K of the section C; but in the latter section there are arranged in the small areas indications of cost which correspond to the superposed indications of quantity on the section B. A third section D corresponds to a portion of the section C, containing the same indications of cost and numerals for the days of the month, but the printing is in reverse order so that when this section is folded to the superposed over the section C corresponding indications in the two sections will register. 95

With the construction as described, in use 110

the sheet when handed to the inspector has filled in thereon the name and address of the consumer and the meter reading of last inspection. After taking the new reading 5 the inspector makes note of the same in the proper line of the portion B', this being above the line for the last reading, and at the same time he subtracts the one from the other and places the difference, or quantity 10 consumed in the line below. If desired a carbon sheet may be provided so that the one entry upon the section B will form an exact duplicate on the corresponding portion of the section C. The inspector then punches the 15 folded sheet at the point indicating the day of the month when the reading is taken, and also selects the number corresponding to the quantity of gas consumed and punches in the small area containing this number. This 20 punching of the upper sheet will simultaneously punch the folded sections, but the date on the section D will be advanced ten days, while the figures in the punched areas C and D represent the amount of the bill. It is 25 customary to allow a discount for payment within the prescribed time limit, such as ten days, and to require the full amount if paid at a later date. This is provided for by placing in each of the areas divided by the 30 transverse lines two numbers, one the full amount of the bill and the other the discounted bill. These, as shown, are arranged with the discounted amount in the upper portion of the area and the full amount in 35 the lower portion so that the inspector may indicate which of these figures is to be paid by punching either in the upper portion or in the lower portion of the area.

After punching the folded sheet the 40 inspector detaches sections C and D leaving them with the customer and returns the section B to the office. The consumer in paying his bill detaches and returns the section D but retains the section C as a memorandum. 45 The bill and amount of payment may be checked at the office by superimposing the return section D with the section B and if the punchings register this will indicate that the amount of payment is correct. 50 My improvement simplifies the system of accounts, dispensing with all computation in the central office and requiring of the inspector, in addition to the usual operation of reading the meter, only the punching of the 55 slips and detaching the sections.

It is occasionally necessary to render a bill for more than one month and for the quantity recorded at a previous reading. To provide for this I have arranged in the recording space B' a sufficient number of 60 lines to record more than two readings and the difference between the same; also a line for the total quantity consumed. These additional lines are not ordinarily used but can be employed whenever necessary. 65

What I claim as my invention is:

1. A blank, comprising a plurality of superposed sections subdivided into small areas in registration with each other, one of said sections having in a portion of the subdivisions thereof quantity indications and in the other portions date indications, and another section having in the areas registering with said quantity indications corresponding cost indications and in the areas registering with said date indications advanced date indications. 70

2. A blank comprising two superposed sections having corresponding portions appropriately designated for the marking of 80 meter readings and name and address of the customer, also portions correspondingly subdivided to be in registration, a portion of said subdivisions of one of said sections containing date indications and another portion 85 thereof containing quantity indications and the corresponding subdivisions of the other section having advanced date indications registering with the first mentioned date indications and having cost indications in registration with said quantity indications, whereby punching of the superposed sections will indicate on one thereof, the date of 90 meter reading and quantity consumed and on the other, the limit date for payment 95 with discount and cost of consumption.

3. A blank, comprising superposed sections subdivided into corresponding registering small areas, the small areas of the upper section having therein a series of 100 quantity indications and the small areas of the lower section each containing full and discounted cost indications in predetermined portions thereof, whereby the punching of the superposed sections will indicate 105 in one section a selected quantity and in the other section selected full or discounted cost corresponding to said quantity.

In testimony whereof I affix my signature.
ALFRED COPONY.
